STOCKING DRIER AND STRETCHER

Joseph Paul Blackman, Fairfield, Conn., assignor
of one-half to Edward F. Hurd, Bridgeport,
Conn.

Application April 20, 1935, Serial No. 17,484

14 Claims. (Cl. 223—77)

This invention relates to new and useful improvements in a stocking drier and stretcher, and has for an object to provide a means adapted to hold any size of stocking in proper shape

5 for drying so as to prevent the stocking getting out of shape and also, if desired, maintain the stocking stretched so as to prevent it from shrinking.

Another object is to provide a stocking stretcher and drier including adjustments whereby it is adapted for use in the drying of various sizes of stockings, the said stretcher and drier having independent simple adjustments so as to properly take care of various foot, ankle 15 and calf sizes of stockings.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the 25 scope of the appended claims.

In the drawing:

Fig. 1 is a side view showing the manner of applying the device to a stocking, the latter being shown in section in full lines and the various 30 dotted lines showing some of the adjustments which may be made so as to have the device stretch the stocking as desired or to fit different sizes of socks or stockings;

Fig. 2 is an elevational view looking at the 35 stretcher and drier from the right in Fig. 1;

Fig. 3 is an enlarged transverse sectional view taken substantially along the line 3—3 of Fig. 2;

Fig. 4 is a similar view taken substantially along the line 4—4 of Fig. 2;

40 Fig. 5 is a similar view taken substantially along the line 5—5 of Fig. 2;

Fig. 6 is an enlarged detail sectional view taken substantially along the line 6—6 of Fig. 2; and

Fig. 7 is a similar view taken substantially 45 along the line 7—7 of Fig. 2.

As here disclosed the improved drier and stretcher comprises front and rear transversely flat tubular leg members 10 and 11 of which the former comprises a calf portion 12 and an ankle portion 13 and it will be noted that the lower end portion 14 of said member, beginning at the ankle portion thereof, in addition to extending downwardly is curved forwardly. The rear leg member 11 comprises a calf portion 15, an ankle portion 16 and below such portion the member

is curved providing a heel portion 17 the free end portion 18 of which is turned up slightly for a purpose to be described.

A flexible piece 19, such for example as flat corset steel, has one end portion 20 (see Fig. 7) secured in the lower free end portion 18 of the leg member 11 and such flexible piece is then inserted through the lower end of the front leg piece 10 and is carried upwardly entirely therethrough and has its other end portion 21 (see 10 Figs. 6 and 7) inserted into the rear leg member 11 through the open upper end thereof. Between the lower ends of the members 10 and 11 the piece 19 forms a loop 22 and between the upper ends of said members the piece forms a 15 loop 23.

The piece 19 is preferably of flexible spring metal, and is slidable through the front leg member 10 and is slidable in the upper portion of the rear leg member 11 so that the piece may be 20 moved through the member 10 and more or less of the piece may be inserted into and withdrawn from the member 11 in the making of adjustments as will later appear. If desired, the leg members 10 and 11 may be round and the piece 25 19 may also be of round stock. However, it is preferred that the tubular leg members be transversely flat, and that the member 19 be of flat stock as shown since if round stock is used in place of the piece 19 and round tubes in place 30 of the flat tubes shown there will be a tendency of the device to turn laterally out of its plane. The members 10 and 11 may be flat seamless tubes or they may be formed of sheet metal folded up to proper shape with longitudinal side 35 edges preferably on the inside as shown at 9.

Disposed at the inner sides of and secured to the front and rear leg members 10 and 11 are flat tubular guide members 24 and 25 respectively. The guides 24 and 25 may be secured to the members 10 and 11 in any suitable manner and by any suitable means as for example by solder as shown at 26. Said guides have their lower end portions 27 and 28 curved to extend toward one another as best shown in Fig. 1 and within the 40 curved lower end portion 28 of the guide 25 there is secured one end 29 of a flexible piece 30. (See Fig. 6). Such flexible piece 30 is preferably of the same material as piece 19 and is carried up entirely through the guide 24 and has its free end 50 31 inserted into the guide 25 through the upper end thereof. Between the upper ends of the guides the piece 30 forms a loop 32 and its portion between the curved lower ends of the guides is 55 designated 33.

From the foregoing description it will be understood that the end 20 of the flexible piece 19 may be secured in the rear leg member 11 in any desired manner. As shown, the end piece is secured 5 by pinching in portions of the member 11 as shown at 34 in Fig. 7. The end of the flexible piece 30 is secured in the curved portion 28 of the guide 25 in a similar manner, portions of said guide being pressed or pinched inwardly against 10 the end 29 of the piece as shown at 35. It should also be understood that while the flexible piece 19 is slidable through the front leg member 10 and into and from the upper end portion of the leg member 11, the flexible piece 30 is slidable 15 through the guide 24 and its free end portion is slidable in and out of the upper end portion of the guide 25. Further, while it is preferred that the front and rear leg members and the guides be in the form of flat tubes they need not be in the 20 form of split tubes as shown but may be seamless or may have their edges secured together.

The device is particularly adapted for use when drying woolen stockings at which time it will serve to maintain a stocking in the required shape so 25 that it may be dried without shrinking. In the drawing a stocking is indicated at 36 and includes a foot portion 37 and a leg portion 38. When the present device is to be used for drying the stocking flexible piece 19 is drawn upwardly 30 through the front leg member 10 so that the lower or foot shaped loop 22 of said piece is relatively small as indicated by its dotted line position 22a in Fig. 1. As the piece 19 is drawn upwardly through the member 10 its free end portion 35 may be further inserted into the member 11 so that the size of its upper loop 23 is not increased.

If the stocking to be dried is quite small, then the piece 31 is drawn upwardly through the guide 40 24 so as to as far as possible reduce the distance between the ends of the curved portions 27 and 28 of the guides, and since the guides are attached to the members 10 and 11 such adjusting of the piece 30 will result in the ankle portions of said 45 members being drawn toward one another. To keep low the distance between the calf portions of the members 10 and 11 the loop 32 of the piece 30 must be kept small and therefore as such piece is drawn upwardly through the guide 24 50 additional portions of the piece are inserted into the guide 25.

Assuming that all of the parts of the device, with the exception of the foot loop 22 of the piece 19, are in the full line positions of Fig. 1, 55 and that such foot loop is in the position of the dotted line 22a then the device may be easily inserted into the stocking preferably until the heel portion 17 of the device engages the heel of the stocking. Thereafter a portion of the piece 19 is drawn out of the upper end of the member 11 and additional quantities of said piece are fed 60 downwardly through the member 10 so as to form the foot-shaped loop 22. The piece is fed as described until the loop 22 is of the desired 65 size completely filling the foot 37 of the stocking in a manner to stretch the same and maintain it in the proper shape. Owing to the fact that the free end portion 18 of the heel 17 is bent upwardly as described the portion of the piece 19 70 forming the foot shaped loop 22 takes a shape with its under or lower arm arched as at 39.

Either after or before the piece 19 has been fed downwardly through the member 10 so as to have the foot-shaped loop 22 of the desired size 75 the flexible piece 30 may be manipulated so as to

shift the members 10 and 11 relatively so as to have such members properly fit or stretch the ankle and calf portion of the stocking. To adjust such members to a larger ankle size of stocking the piece 30 is fed or forced downwardly through 5 the guide 24 so as to increase the size of its loop 33 as to bring such loop into the dotted line position 33a. Obviously, this forces apart the ankle portions 13 and 16 of the members 10 and 11 as shown by the dotted lines and if the size of the 10 upper loop 32 of the piece 30 is kept the same there will be no increase in the calf size for which the members 10 and 11 are set.

If the calf size is to be varied it may be increased by increasing the size of the loop 23 so as 15 to have that loop of a size indicated by a dotted line 23a and by then increasing the size of the loop 32 as to that indicated by the dotted lines 32a. The calf size may be reduced by reducing the size of the loop 23 as to the size indicated by 20 the dotted lines 23b. Beyond certain limits variations in the calf sizes must be taken care of by adjusting the sizes of the loops 23 and 32 although within limits varying the size of either 25 loop will vary the distance between the upper portions of the members 10 and 11. It will be understood that the sizes of the loops 23 and 32 are adjusted by inserting the free end portions of the pieces 19 and 30 more or less into the member 11 30 and the guide 25 respectively.

For a very large stocking the parts may be adjusted to hold such stocking in the proper shape and the parts may also be adjusted so that the device will hold a small stocking in shape. It will, therefore, be appreciated that the one device 35 is capable of taking care of all sizes of stockings and that it is not necessary to have a different pair of devices for each size of stocking. The dotted lines 22b indicate a substantial increase in 40 the size of the foot loop beyond that shown by the full lines and give some idea of the wide range of adjustments which may be made.

With the disclosed means adjustments may be made to exact sizes since the adjustments are not 45 made step by step. Further, the adjustments are not dependent on one another and may be made independent of one another so as to give the best results. That is, the foot loop may be expanded to the desired size without respect to the ankle size or calf size and by adjusting the width of 50 the loop 33 the ankle size may be regulated without respect to the calf or foot size and by adjusting either or both of the loops 23 and 32 the calf size may be adjusted without respect to the ankle or foot size. For insertion into and removal from 55 a stocking the device may be readily adjusted to small or if desired to its smallest dimensions so that there will be no difficulty in the use of the device. In this connection it will be understood that to reduce the size of loop 22 the piece is 60 drawn upwardly through the front leg member 10. To reduce the ankle size the piece 30 is drawn up through the guide 24 and to reduce the calf size the loops 23 and 32 are reduced as by 65 feeding the pieces 19 and 30 into the member 11 and guide 25 respectively.

Having thus set forth the nature of my invention, what I claim is:

1. In a stocking drier and stretcher, front and 70 rear tubular leg members of which the former comprises a calf and ankle piece while the latter comprises a calf, ankle and heel piece, a flexible resilient piece extending out of the lower end of one of said members and into the other through 75 the lower end thereof to form a flexible resilient

loop, and said flexible piece being slidable in one of said members independently of the other member to form foot shaped loops of different sizes.

2. In a stocking drier and stretcher, front and

5 rear tubular members each having its lower end portion curved forwardly, a flexible resilient piece extending between the lower ends of said members and having its end portions disposed in said members to form a flexible resilient loop between them, and said piece being frictionally slidable in one of said members independently of the other member to form foot shaped loops of different sizes.

3. In a stocking drier and stretcher, front and

15 rear tubular members of which the former comprises a calf and ankle piece while the latter comprises a calf, ankle and heel piece, said front piece having its lower end curved forwardly, a flexible resilient piece extending between the lower ends 20 of said members and having its end portions disposed in said members, said piece being slidable in one of the members so that it is adapted to be fed out of the lower end of said member to form a foot shaped loop of the desired size, and said rear 25 member having the free end portion of its heel piece bent slightly upwardly so as to bend the flexible piece forming the foot shaped loop and because of its resiliency curve the portion immediately forwardly of the heel to form an arch.

30 4. In a stocking drier and stretcher, front and rear leg members each comprising a calf and an ankle portion, a flexible piece extending between the lower ends of said members and adjustable with respect to one of them to form a foot shaped 35 loop of the desired size, and separate means between and connecting said members above said footloop adjustable to vary the distance between their ankle portions.

5. In a stocking drier and stretcher, front and 40 rear leg members each comprising a calf and an ankle portion, a flexible piece extending between the lower ends of said members and adjustable with respect to one of them to form a foot shaped 45 loop of the desired size, and separate means connecting said members above the footloop and adjustable to vary the distance between their calf portions.

6. In a stocking drier and stretcher, front and rear leg members each comprising a calf and an ankle portion, a flexible piece extending between the lower ends of said members and adjustable with respect to one of them to form a foot shaped 50 loop of the desired size, and separate means connecting said members above the footloop and adjustable to independently vary the distances 55 between the ankle portions and between the calf portions of said members.

7. In a stocking drier and stretcher, first and 60 second tubular members, a flexible piece having an end secured in the second of said members, said piece extending through the first of said members from the lower end thereof and having its other end disposed in the upper portion of the second of said members, said piece withdrawable from the upper end of the second member to increase the distance between the upper ends 65 of said members, and said piece shiftable down through the first member to form a foot shaped loop at the lower ends of said members.

75 8. In a stocking drier and stretcher, first and second tubular members, a flexible piece having an end secured in the second of said members, said piece extending through the first of said members from the lower end thereof and having its other end disposed in the upper portion of the

second of said members, and said piece withdrawable from the upper end of the second member to increase the distance between the upper ends of said members.

9. In a stocking drier and stretcher, first and 5 second tubular members, a flexible resilient piece having an end secured in the second of said members, said piece extending through and frictionally slidable in the first of said members from the lower end thereof to form a flexible resilient 10 loop between the members, and said piece being shiftable down through the first member to form and adjust a foot shaped loop at the lower ends of said members.

10. In a stocking drier and stretcher, front and 15 rear leg members each comprising a calf and an ankle portion, a flexible resilient piece extending between the lower ends of said members and adjustable with respect to one of them to form a foot shaped loop of the desired size, tubular guides 20 on said members, a flexible resilient piece having an end secured in the first of said guides, said piece extending through the second of said guides from the lower end thereof and having its other end disposed in the upper portion of the first 25 guide, said piece withdrawable from the upper end of the first guide to increase the distance between the upper ends of said members, and said piece shiftable down through the second guide to increase the distance between the lower portions 30 of said members.

11. In a stocking drier and stretcher, front and 35 rear leg members each comprising a calf and an ankle portion, a flexible resilient piece extending between the lower ends of said members and adjustable with respect to one of them to form a foot shaped loop of the desired size, tubular guides 40 on said members, a flexible resilient piece having an end secured in the first of said guides, said piece extending through the second of said guides from the lower end thereof and having its other end disposed in the upper portion of the first guide, and said piece withdrawable from the upper end of the first guide to increase the distance 45 between the upper ends of said members.

12. In a stocking drier and stretcher, front and rear leg members each comprising a calf and an ankle portion, a flexible resilient piece extending between the lower ends of said members and adjustable with respect to one of them to form a 50 foot shaped loop of the desired size, tubular guides on said members, a flexible piece having an end secured in the first of said guides, said piece extending through the second of said guides from the lower end thereof, and said piece shiftable 55 down through the second guide to increase the distance between the lower portions of said members.

13. In a stocking drier and stretcher, first and 60 second tubular members, a flexible resilient piece having an end secured in the second of said members, said piece extending through the first of said members from the lower end thereof and having its other end disposed in the upper portion of the second of said members, said piece withdrawable 65 from the upper end of the second member to increase the distance between the upper ends of said members, said piece shiftable down through the first member to form a foot shaped loop at the lower ends of said members, 70 tubular guides on said members, a flexible piece having an end secured in the first of said guides, said piece extending through the second of said guides from the lower end thereof and having its other end disposed in the upper portion of the 75

first guide, said piece withdrawable from the upper end of the first guide to increase the distance between the upper ends of said members, and said piece shiftable down through the second 5 guide to increase the distance between the lower portions of said members.

14. In a stocking drier and stretcher, a pair of tubular members forming front and rear leg

members, a flexible resilient member extending between the lower ends of said tubular members to form a foot loop and frictionally slideable in one of said members to adjust the size of the loop, and a separate connection between the tubular members above the foot loop and adjustable to vary the distance between said members. 5

JOSEPH PAUL BLACKMAN.
